STRAND-FEEDING DEVICE FOR KNITTING
AND LIKE MACHINES

Robert H. Lawson, Pawtucket, R. I., assignor to
Scott & Williams, Incorporated, Laconia, N. H.,
a corporation of Massachusetts

Application August 19, 1938, Serial No. 225,760

16 Claims. (Cl. 66—132)

This invention consists in a device for feeding or delivering elastic or non-elastic strands to knitting and like machines to maintain a uniform elongation of, or a constant tension on, the strands as they are taken up by the fabric.

One object of the invention is to provide a device of the type indicated adapted to feed a strand or strands intermittently in accordance with their take-up during the reciprocating operation of a knitting or like machine.

Another object of the invention is to provide a device of the type indicated for intermittently feeding the strand or strands to the fabric in timed relation to the reciprocation of the strand-guide or guides which traverse them back and forth across the knitting needles in forming the courses of loops in the fabric.

Another object of the invention is to provide in a device of the type indicated means for operating the strand-feeding device with a variable speed in accordance with the change in reciprocating speed of the strand-guide or guides.

Another object of the invention is to provide a strand-feeding device particularly adapted for feeding elastic strands such as rubber threads to maintain a uniform elongation thereof between the feeding means and the fabric.

Another object of the invention is to provide a strand-feeding device of the type indicated which is adapted for attachment to knitting machines of standard type without material alteration in the structure or arrangement thereof.

Another object of the invention is to provide a strand-feeding device of the type indicated in which the mechanism is of simple construction, efficient in operation and proof against derangement or getting out of order.

Further objects of the invention are set forth in the following specification which describes two embodiments of the device, by way of example, as illustrated by the accompanying drawings.

In the drawings:

Fig. 1 is a front elevational view of a "Lamb" type knitting machine for producing flat fabrics showing the present improved device as applied to use therewith;

Fig. 2 is an end view of the same;

Fig. 3 is a view similar to Fig. 1 showing the reciprocating means for the elastic and yarn strands in positions opposite to that shown in Fig. 1;

Fig. 4 is an end view of a portion of the strand-feeding device showing the driving means for the feed-roll;

Fig. 5 is a detailed view of the means for inter-

mittently traversing the belt or chain which drives the feed-roll;

Figs. 6 to 9, inclusive, are diagrammatic views illustrating different positions of the means for traveling the feed-roll drive-belt or chain in comparison with the different positions of the strand-guides of the knitting machine;

Fig. 10 is a diagrammatic view illustrating the path of movement of the elastic strand in comparison with the rotary motion of the feed-roll; 10

Fig. 11 is an elevational view of a modified form of the strand-feeding device;

Fig. 12 is a plan view of a portion of the same showing the feed-roll;

Fig. 13 is an enlarged sectional view of the feed-roll on line 13—13 of Fig. 11; 15

Fig. 14 is an end view of a portion of the knitting machine shown in connection with the strand-feeding device;

Fig. 15 is a plan view of the same, part sectional on line 15—15 of Fig. 11; 20

Fig. 16 is an enlarged sectional view of the feed-roll driving means taken on line 16—16 of Fig. 11; and

Fig. 17 is a rearward view of the feed-roll driving means showing the shifting pawl. 25

The present invention is herein illustrated as applied to a "Lamb" type knitting machine arranged for knitting flat fabrics from textile yarns and/or elastic strands. The machine is 30 arranged for plating the yarns, that is for simultaneously knitting two strands side by side and the strands may be both of textile material or one strand may be elastic and the other non-elastic. In the present application, however, I 35

have preferred to illustrate the strand-feeding means as adapted for feeding an elastic strand in plating it with a textile strand so that the textile strand appears on the outer surfaces of the fabric while the elastic strand is knitted into 40

the center thereof and hidden by the yarn. A textile thread or yarn such as cotton, silk, rayon or the like and a rubber or other elastic strand are thus plated to form elastic webbing or the like with the rubber hidden from view. In this 45

type of machine two reciprocating guides are employed for traversing the different strands, one for the textile strand and the other for the elastic strand. The guide for traversing the yarn strand is mounted fixedly on the reciprocating 50

carriage of the machine, while the guide for the elastic strand is pivotally mounted thereon to adapt it to have a limited swinging movement with respect to the yarn-guide. During the plating operation the yarn strand precedes the elastic strand.

tic strand in its traverse back and forth across the width of the fabric in forming the courses of loops. The guides for the yarn and elastic strands have an extent of traverse slightly greater than the distance between the edges of the fabric, before the direction of their traverse is reversed, whereby to provide that all the needles will have been manipulated before the reverse stroke is started. As the guide for the yarn strand reverses its movement the guide for the elastic strand is rocked across center to assume a position rearwardly of the yarn-guide. In supplying the elastic strand to its guide it is therefore necessary that the feed be intermittent and coincident or synchronized with the traverse of the guide and the take-up of the strand by the fabric. For this purpose the present invention provides a device operated directly from the reciprocating means of the knitting machine for intermittently rotating the feed-roll at a definite speed to maintain a uniform elongation of the elastic strand. It is also noted that the traversing means of the knitting machine is usually driven by a crank-motion and therefore the turning of the feed-roll which is operated directly from the traversing means will have a varying speed in accordance with the motion of the crank.

Referring to Figs. 1 and 2 of the present drawings, the reference character 2 designates a bench or table surmounted by an angular bracket 3 to which the head 5 of the knitting machine may be attached in any suitable manner as by means of clamp-screws 6. The machine head 5 is of usual construction comprising a triangular portion 7 mounting the needle bed 8 in which the knitting needles 9 are reciprocable by means of suitable cams, not herein shown.

A triangularly-shaped carriage 10 has opposite runners 11 mounted to slide in grooved ways 12 fast on the machine head 5. The carriage 10 is reciprocated by means of a crank-motion 15 shown at the right in Figs. 1 and 3. In the form as herein illustrated, the crank-motion comprises a crank 16 fast on the end of a shaft 17 which is journaled in a bearing on a standard or bracket 18 mounted on the table 2 at the right of the knitting head. At its opposite end the shaft 17 carries a bevel-gear 19 in mesh with a smaller bevel-pinion 20. The pinion 20 is fast on the end of a shaft 21, also journaled in a bearing on the standard 18, and carries fast and loose pulleys 22 and 23 at its outer end. The shaft 21 may be driven from a belt passing around the fast pulley 22 to thereby rotate the pinion 20 and drive the gear 19 to rotate the crank 16. Connected to the crank-pin 25 is a piston or connecting rod 26, the opposite end of which is pivotally joined to a stud 27 projecting through a boss at the end of an arm 28 on the carriage 10.

The carriage 10 straddles the needle-bed 8 saddlewise and fastened to its forward inclined side is a yarn-guide 30. The yarn-guide 30 is of angular shape with a portion projecting downwardly towards the top of the needles 9 and provided at its end with an eye 31 through which the strand of yarn y leads. The guide 32 for the elastic strand is of somewhat different form having a head at one end adjacent the top of the needles 9 with an eye 33 for the elastic strand r to pass through and an auxiliary guiding eye on a projection 34 on the head. Referring particularly to Fig. 3, the guide 32 is pivoted to the rearward side of the carriage 10 at 35 to adapt it to rock back and forth to a limited extent with respect to the fixed yarn-guide 30. The rocking

motion of the strand-guide 32 is limited by the confines of a slot in a cover 36 overlying the guide. The elements thus far described vary in construction with different types of machines, but suffice it to state that they constitute the main operating mechanism of the knitting machine when adapted for plating and with which the present device cooperates.

The device of the present invention consists essentially in a feed-roll 40 for delivering the elastic strand with its driving means actuated from the traversing carriage 10 of the knitting machine to intermittently rotate the feed-roll. In a preferred embodiment of the invention, as shown in Figs. 1 to 4, inclusive, the feed-roll 40 is driven from a link-belt or chain 41 through means as next described. The feed-roll 40 may be of frusto-conical shape, as shown in Figs. 1 and 3, and is mounted fast on a shaft 42 journaled in bearings in the forks of a bifurcated bracket 43. The feed-roll 40 is located above the knitting machine and may be conveniently mounted on an upright or standard in the form of a rod 44 supported in a step-bearing 45 secured to the top of the table 2. The bracket 43 may be attached to a block or mounting 46 bored to receive the rod 44 and secured fast thereon by means of a set-screw 47. A sprocket-wheel 48 fast on the end of the shaft 42 is employed for driving the roll from the link-belt or chain 41. The conical form of the feed-roll 40 provides for regulating the extent of feed of the elastic strand r at each rotation of the roll by causing the strand to make a greater or lesser amount of wrap around the roll. To hold the strand to its adjusted position on the tapered surface of the roll a presser roller 49 may be employed. As herein shown, the presser roller 49 is journaled between opposite arms 50 pivoted to a support 51 which is slidable along the horizontal portion of an angular bracket 52 attached to the bracket 43. A helical spring 53 anchored to the support 51 is connected to the arms 50 to press the roller 49 against the strand r as it leads around the feed-roll 40.

The chain 41 for driving the feed-roll 40 leads downwardly from the sprocket-wheel 48 to a pair of sprockets 55 and 56 and is thence directed laterally in two parallel horizontal paths as it passes around a third sprocket 57. The sprocket-wheels 55 and 56 are journaled on studs 58 secured in the upright portion 59 of an L-shaped bracket 60 which may be supported on the vertical standard or rod 44. For this purpose the bracket 60 is secured to an arm 61 mounted on the rod 44 and fastened thereto by means of a set-screw 62. The sprocket 57 is journaled on a stud 63 which is secured fast in an elbow-shaped member 64 mounted to slide on the horizontal portion of the L-shaped bracket 60. The offset portion 60 of the member 64 seats across the top of the horizontal portion of the bracket 60 and a bolt 65 passing through a slot 66 in the bracket has a nut on its end for clamping the member 64 in fixed position. By this means the member 64 may be slid longitudinally of the horizontal portion of the bracket 60 and secured in position to tighten the belt or chain 41 passing around the series of sprockets.

The chain 41 is traversed intermittently, always in the same direction, by means carried on the reciprocating carriage 10 of the knitting machine. Mounted on an offset arm 69 which rises from the carriage 10 is a bracket 70 secured fixedly thereto by screws 71. The bracket 70

carries a pair of rearwardly-projecting pins 72 and 73 which are adapted to engage with inclined hooks 75 on the transmission belt or chain 41. The upper pin 72 is arranged to engage with the hooks 75 on the upper reach of the chain 41, while the lower pin 73 engages with the hooks on the lower reach of the chain; the pin 73 being disposed in offset relation with respect to the pin 72 by being mounted on an L-shaped arm 76 10 screwed to the rearward side of the bracket 10.

From the foregoing description, it will be apparent that when the carriage 10 moves to the right, as viewed in Fig. 1, the pin 73 will engage with one of the hooks 75 on the lower reach of 15 the chain 41 to traverse the latter in the same direction. On the other hand, when the traverse of the carriage 10 is reversed the pin 72 will engage one of the hooks on the upper reach of the chain 41 to traverse this portion of the chain 20 to the left in the manner indicated in Fig. 3. In this way the chain is given an intermittent traversing motion in the same direction during each reciprocation of the carriage 10 in either direction, the result being to cause the feed-roll 25 40 to be rotated in the direction indicated by the arrow in Fig. 2 whereof to feed the elastic strand *r* downwardly to the guide 32 of the knitting machine. It is to be noted that the speed of the roll 40 is adjusted to feed the elastic strand *r* 30 at such a rate that it will be elongated between the roll and the guide 32, variations in the rate of feed being effected by regulating the position of the strand on the tapered surface of the roll 40. That is to say, if a greater or lesser rate of 35 feed is required the strand may be shifted one way or the other on the surface of the feed-roll 40 to cause the latter to pay off more or less of the strand at each rotation of the roll.

When the lower pin 73 is traversing the lower 40 reach of the chain 41 to the right the hooks 75 on the upper reach of the chain will slide over the upper pin 72 in the manner of a ratchet as indicated in the detailed view, Fig. 5. That is to say, the upper reach of the chain will be raised 45 slightly to allow the inclined portions of the hook to slide across the pin 72 and the same is true as regards the passage of the hooks over the lower pin 73 when the direction of traverse of the carriage 10 is reversed. In order that the lower 50 reach of the chain shall not sag to the extent that the pin 73 will not engage properly with the hooks 75 a hold-up spring 77 may be arranged on the under side of the chain as shown in Fig. 1. The spring 77 may be of the leaf-type fastened to 55 a ledge on a bracket 78 secured to the bracket 60. The arcuate portion of the spring 77 underlies the lower reach of the chain 41 to adapt the latter to slide freely thereover and a similar arcuately curved spring 79 fastened to the upper portion 60 of the bracket 78 may be located to bear against the upper reach of the chain 41. The purpose 65 of this latter spring is to prevent the chain 41 from vibrating or jumping to throw its hook 75 out of range of the pin 72. The springs 77 and 79 are adapted to yield readily as the pins 72 and 73 pass the hooks in the manner indicated in Fig. 5. The construction and arrangement of a preferred form of the present invention having now 70 been described, the method of operation of the device will next be explained.

When power is applied to the drive-pulley 22 its shaft 21 rotates the pinion 20 to turn the gear 19 and shaft 17 carrying the crank 16. The crank 16 acts through the connecting rod 26 to 75 reciprocate the carriage 10 back and forth with

respect to the needles 9 as the latter are manipulated through the action of suitable cams, not herein shown or described. As the carriage 10 reciprocates in opposite directions it traverses the guides 30 and 32 across the row of needles 9 and the courses of loops are formed to plate the two strands *y* and *r* into the fabric. As before noted, the textile strand *y* precedes the elastic strand *r* during each traverse of the carriage in either direction, the rocking motion of the guide 32 providing for its shift in position at the end of each stroke of the carriage.

Referring particularly to the diagrammatic views, Figs. 6 to 9, inclusive, of the drawings, Fig. 6 illustrates the guides in position at the right-hand edge of the fabric at the point where the strands are being carried back to the left. As the guides 30 and 32 are traversed toward the left to the position indicated in Fig. 7 the upper pin 72 comes into engagement with one of the hooks 75 on the upper reach of the chain 41 and the chain is given a traversing motion in the direction indicated by the arrows in Fig. 1 to cause the feed-roll 40 to be rotated. As the feed-roll 40 is rotated in the direction indicated by the arrow in Fig. 2 the elastic strand *r* will be fed to the fabric in synchrony with the reciprocating movement of the guide 32 and with the required elongation in accordance with the rate of feed of the strand. Fig. 8 illustrates the guide 32 as 30 having reached the end of its traverse to the left and as having been rocked to a position opposite to that shown in Fig. 6. It will be noted that the strand *r* is carried outwardly somewhat beyond the edge of the fabric *F* and the yarn-guide 30 35 may proceed to a slight extent beyond this edge of the fabric in order that the needles may complete their cycle in the operation of the knitting machine. The carriage 10 is thereafter moved toward the right and when it arrives at the position shown in Fig. 9, the lower pin 73 will come 40 into engagement with one of the hooks of the bottom reach of the chain 41 to cause the latter to be again traversed to rotate the feed-roll 40 to an extent sufficient to pay off the strand *r* as it is 45 taken up by the fabric during its course thereacross. It is here noted that the spacing of the hooks 75 on the chain 41 is such that the traverse of the chain 41 in either direction starts at the point where the guide 32 is positioned inwardly 50 from the edge of the fabric at a distance substantially equal to the distance the guide moves outwardly beyond the edge of the fabric and thus the turning of the roll 40 and the feed of the strand *r* is synchronized with the cooperative action of the guide and the needles. On the other 55 hand, the traverse of the chain may continue after the guide 32 has passed beyond the opposite edge of the fabric but the length of the strand *r* paid out at this time will be taken up as the guide 60 32 reverses its motion. This method of feeding the elastic strand is illustrated graphically in Fig. 10 of the drawings, the full lines representing the path of the guide 32 for the strand *r* during the rotary action of the feed-roll and the dotted lines indicating the path of the strand *r* 65 while the feed-roll is stationary.

Figs. 11 to 17, inclusive, illustrate a modified form of construction of the invention wherein the reciprocating motion of the carriage is translated into rotary motion of the feed-roll from the rotation of a frictionally-driven pulley. Referring to Figs. 11 to 13, the feed-roll 80 for the elastic strand *r* is of substantially the same arrangement as that previously described. The

roll 80 is fast on a shaft 81 journaled in the bearings 82 of a forked bracket 83 which is attached to a shelf 85 mounted fast on a standard or rod 86 supported in a step-bearing 87 secured 5 to the table of the knitting machine. A pressure roll 88 is journaled at the end of arms 89 pivoted to an elbow-shaped bracket 90 fastened to the shelf 85; being pressed into contact with the strand *r* by means of a spring 91. The strand *r* leads from its supply, not herein shown, through a pigtail-guide 92, is given a full turn around the periphery of the feed-roll 80, and thence feeds down through a second pigtail-guide 93 to the reciprocating traverse-guide 95 of the knitting machine shown in Figs. 14 and 15.

10 Suitable stopping mechanism is usually provided for arresting the operation of the knitting machine when the strand breaks or its supply is exhausted, an electrical stop-device being shown in Figs. 11 to 13, but not herein described as it forms no part of the present invention.

Fastened to the reciprocating carriage 96 of the knitting machine by means of angle-shaped brackets 97 and 98 is a rectangularly-shaped frame 100, shown most clearly in Figs. 11 and 15. The frame 100 comprises top and bottom horizontal strips or bars 101 and 102 tied together by three crossbars 103. Overlying the back of the two horizontal strips 101 and 102 of the frame 100 are two similar shorter strips or bars 104 and 105, one at the top to the left and the other at the bottom to the right. The bars 104 and 105 have secured to their edges strips 106 and 107 of fiber, leather or other suitable material for providing a friction drive. The bars 104 and 105 are fastened to the horizontal strips 101 and 102 by means of screws 108 passing through slots 109 and 110 in the bars and screwed into the strips as shown in Figs. 11 and 16. By this means the bars 104 and 105 may be adjusted longitudinally of the frame 100, it being noted that the fiber or leather material underlies the edge of the upper strip 101 and overlies the top of the strip 102 of the frame 100 to provide a relatively broad contact surface. The two fiber strips 106 and 107 are adapted to make contact with a friction drive-wheel 115 having its periphery covered with a similar material.

The drive-wheel 115 is of slightly less diameter than the distance between the faces of the two fiber strips 106 and 107 so that its periphery will engage with only one face at a time, means being provided for shifting the axis of the wheel vertically to cause it to alternately engage first one contact strip and then the other strip. For this latter purpose the wheel 115 is mounted on a stud 116 projecting from the end of a rotary shaft or spindle 117 in eccentric relation to the axis thereof. The shaft 117 is mounted in a bearing 118 at the top of a bracket or standard 119 secured to the bench or table of the knitting machine. Pinned or otherwise made fast to the rearward end of the shaft 117 is an arm 120 which acts as a crank or pawl to rock the shaft to raise and lower the friction wheel 115. The pawl 120 is thrown across center by means carried on the reciprocating frame 100 and is limited in its rocking movement by a pair of stops 121 and 122 on the standard 119 as shown most clearly in Figs. 14 and 17. A helical spring 123 anchored to the base of the standard 119 is secured to a pin 124 projecting rearwardly from the end of the arm or pawl 120 to adapt it to act resiliently to maintain the pawl in whichever position it may be shifted to. Fast on the

stud 116 at the rear of the friction-wheel 115 is a grooved pulley 125, the wheel and pulley being keyed together by suitable means such as the screw 126 shown in Fig. 16. The pulley 125 is connected to drive the feed-roll 80 by means of an elastic belt 127 passing around a smaller pulley 128 secured fast to the shaft 81 on which the feed-roll 80 is mounted. The elasticity of the belt 127 provides for the vertical movement of the pulley 125 during the shifting of the frictional drive-wheel 115.

Referring to Figs. 11 and 14, it will be noted that when the arm or pawl 120 is thrown to the right the drive-wheel 115 will be carried into its lowermost position to engage its periphery with the fiber strip 107 at the right-hand lower end of the frame 100. When the pawl 120 is rocked to the left it will raise the friction-wheel 115 to engage its periphery with the opposite fiber strip 106, the reversal in the position of the drive-wheel being made at each end of the traverse of the frame 100 moving with the carriage 96. The pawl 120 is shifted by means of wedge-blocks 130 and 131 carried on a U-shaped frame 132 projecting rearwardly from the main frame 100, as shown in Figs. 11, 14 and 15. The wedge-blocks are slotted longitudinally to adapt them to straddle the horizontally-extending rearward bar 133 of the U-shaped frame 132 fastened to the back of the frame 100. Screws 134 passing through slots 135 in the bar are provided for holding the wedge-blocks in position while permitting them to be adjusted longitudinally of the frame 100. It will be observed by reference to Fig. 11 that when the frame 100 is moving in the direction indicated by the arrow in Fig. 11 the right-hand wedge-block 131 will engage the pawl 120 to rock it across center to raise the friction-wheel 115 away from the contact strip 107; while, on the other hand, when the frame 100 is moving in the opposite direction the left-hand wedge-block 130 will engage the pawl 120 to rock it across center to release the friction-wheel 115 from the upper strip and throw it down into engagement with the lower strip. The method of operation of the complete device as embodied in this last-described construction is as next explained.

Assuming that the carriage 96 of the knitting machine is moving toward the left and carrying the frame 100 in the direction indicated by the arrow in Fig. 11 the drive-wheel 115 will be in engagement with the lower friction strip 107 whereby it is rotated in a clockwise direction. The pulley 125 at the rear of the friction-wheel 115 will therefore turn the connected pulley 128 to rotate the feed-roll 80 in counterclockwise direction as viewed in Fig. 13. The strand *r* will thus be fed downwardly to the guide 95 on the carriage 96 of the knitting machine with an elongation therein which is regulated by adjusting the position of the wrap of the strand on the tapered surface of the roll 80. As the knitting machine carriage 96 and frame 100 approach the limit of their traverse to the left the wedge-block 131 will come into contact with the arm or pawl 120 and as the movement of the frame is continued the pawl will be rocked across center to turn the shaft or spindle 117 and thereby shift the position of the eccentric stud 116 to lift the drive-wheel 115 away from the friction strip 107. Immediately the drive-wheel 115 is released from the strip 107 on the frame 100 its rotation will be arrested while as the pawl 120 comes into contact with the stop 121, see Fig. 17, the drive-

wheel will be raised to a position for its periphery to contact with the upper friction strip 106. Then as the direction of traverse of the frame 100 is reversed during the reciprocation of the strand-guide 95 in the opposite direction to plate another course of the two strands into the fabric the frame 100 will be moved to engage the strip 107 with the periphery of the drive-wheel 115. The position of the strips 106 and 107 on the frame 100 and the relationship of the wedge-blocks 130 and 131 thereto is adjusted so that there is an interval before the wheel 115 is engaged with the strip 106. In other words, there is a lag between the intervals of rotation of the wheel 115 under the driving action of the two strips 106 and 107, this lag or pause occurring as the strands are carried out beyond the edges of the fabric at each stroke of the carriage in either direction.

As the strip 106 comes into engagement with the periphery of the wheel 115 during the traverse of the carriage 96 and frame 100 to the right, as viewed in Fig. 11, the wheel will be rotated in the same direction as previously to again turn the pulley to cause the pulley 125 to drive through the belt 127 and pulley 128 to rotate the feed-roll 80 forwardly in the manner as explained before. Rotation of the wheel 115 and the feed-roll 80 driven therefrom will continue for an interval until the left-hand wedge block 130 strikes the pawl 120 and rocks it back into the position shown in Fig. 11 at which juncture the wheel will again engage the lower friction strip 107 to be driven from the movement of the frame 100 towards the left. In this way the friction-wheel 115 is driven intermittently to rotate the feed-roll 80 to periodically feed a length of strand *r* to the thread-guide 95 in synchrony with the reciprocation of the latter in laying the courses of strand material across the fabric.

It will be observed from the foregoing that the present invention provides two preferred forms of construction of an ingenious device for translating reciprocatory motion into rotary motion to feed elastic strands, either uncovered or covered, to knitting and like machines while preserving a uniform elongation of the strand as it is taken up by the fabric. On the other hand, as before stated, my improved strand-feeding means is equally well adapted to deliver one or a plurality of non-elastic strands such as yarns to a knitting machine, for example, in full-fashioned machines employing yarn-control or yarn-furnishing devices such as shown in U. S. Letters Patent No. 1,420,530 to Drumheller, issued June 20, 1922, or U. S. Letters Patent No. 1,562,829 to Howie, issued November 24, 1925. In the former case the conical feed-rolls and in the latter case the toothed yarn-furnishing wheels may be driven by the mechanism of the present invention. In either case, the mechanism operates efficiently to effect the feed of the strand or strands in perfect harmony or synchrony with the knitting operation whereof the fabric produced in the machine is maintained uniform in texture and finish. When an elastic strand is being knitted the rubber strand is hidden between the opposite surfaces of the fabric due to the tension imposed thereon as set forth in U. S. Letters Patent No. 2,009,361, to John Lawson, dated July 23, 1935.

While the invention is herein shown as embodied in two preferred forms of construction, it is to be understood that other modifications may be made in the structure and arrangement of the parts without departing from the spirit

or scope of the invention. Therefore, without limiting myself in this respect, I claim:

1. In a strand-feeding device for knitting and like machines, the combination of a rotary strand-feeding element, a flexible transmission means for rotating the strand-feeding element, said transmission means extending in opposite parallel courses, a reciprocatory member, and means actuated by said reciprocatory member to alternately engage opposite courses of the transmission means to rotate the strand-feeding element in a given direction.

2. In combination with the reciprocating means of a knitting or like machine, a rotary strand-feeding means, a belt for rotating the strand-feeding means, and means for intermittently engaging the reciprocating means with the belt to drive the strand-feeding means in synchrony with the knitting operation.

3. In a knitting or like machine, the combination of traversing means for a strand, means for reciprocating the traversing means, a rotary element for feeding the strand, a chain for rotating the strand-feeding means, said chain being directed in opposite courses parallel to the path of the reciprocating means, and means for engaging the reciprocating means alternately with the opposite courses of the chain to rotate the strand-feeding means in synchrony with the traversing means.

4. In a knitting or like machine, the combination of means for traversing a strand, means for reciprocating said traversing means, a rotary element for feeding the strand, a chain for rotating said element, said chain leading in opposite courses in parallel relation to the path of the reciprocating means, hooks spaced at intervals on said chain, and means actuated by the reciprocating means for alternately engaging the hooks on the opposite courses of the chain.

5. In a knitting or like machine, the combination of strand-traversing means, means for reciprocating the strand-traversing means, a rotary strand feeding element, a sprocket connected to said element, a chain engaging the sprocket, idler sprockets for directing said chain in opposite courses in parallel relation to the path of the reciprocating means, and means carried by the reciprocating means for alternately engaging with the chain in its opposite courses to intermittently travel the chain to rotate the feeding element in a given direction.

6. In a knitting or like machine, the combination of means for traversing a strand, means for reciprocating the traversing means, a rotary strand-feeding element, a belt for rotating said element, and means operated by and with the reciprocating means for periodically engaging the belt at different points therealong to travel the latter in one direction to rotate the strand-feeding element.

7. In a knitting or like machine, the combination of means for traversing a strand, means for reciprocating the traversing means in opposite directions, a rotary strand-feeding element, a belt connected to rotate the strand-feeding element, means for directing said belt in opposite courses in parallel relation to the path of the reciprocating means, inclined hooks on the belt arranged at intervals therealong, and means carried by the reciprocating means and adapted to engage the hooks of one course when moving in one direction and to engage the hooks of the opposite course in moving in the reverse direction whereby to travel the belt in the same direction.

to intermittently rotate the strand-feeding element.

8. In combination with the reciprocating means of a knitting or like machine, strand-feeding means therefor comprising a rotary element engaged by the strand, a friction-wheel connected to rotate the strand-feeding element, and means actuated from the reciprocating means of the machine to alternately engage the opposite sides 10 of the friction-wheel to intermittently turn the latter to rotate the strand-feeding element.

9. In combination with the reciprocating means of a knitting or like machine, strand-feeding means therefor comprising a rotary element engaged by the strand, a friction-wheel connected to drive the strand-feeding element, a rectangular frame connected to be reciprocated from the reciprocating means of the machine, and friction means on said frame for alternately 20 engaging the opposite sides of the friction-wheel to turn the latter in the same direction to intermittently rotate the strand-feeding element.

10. In a strand-feeding device for knitting and like machines, the combination with the reciprocating means of the machine, of a rotary strand-feeding element, a friction-wheel connected to rotate said element, means connected with the reciprocating means of the machine and alternately engageable with the opposite sides of the 30 friction-wheel, and means for automatically shifting the relative position of the friction-wheel and said engaging means to cause the latter to engage first one side of the wheel and then its opposite side as the direction of reciprocation of the reciprocating means is reversed.

11. In a strand-feeding device for knitting and like machines, the combination with the reciprocating means of said machine, of a rectangular frame reciprocated therefrom, friction 40 strips on the opposite horizontal sides of said frame, a wheel having friction means on its periphery adapted to be engaged by the friction means on the frame, a rotary strand-feeding means connected to be driven from said friction-wheel, and means for shifting the position of the friction-wheel to adapt it to engage the friction means on first one side and then the opposite side of the frame as the latter is reciprocated in opposite directions.

50 12. In a strand-feeding device, the combination with a reciprocating frame having parallel bars provided with friction surfaces, a wheel having friction means on its periphery for engaging with the friction means on the frame, a rotary strand-feeding element connected to be rotated from said wheel, means to reciprocate the frame, and means for automatically shifting the relative position of the frame and wheel to cause the latter to engage the friction means on one bar of the frame

as the latter moves in one direction and to engage the friction means on the opposite bar as the frame moves in the opposite direction.

13. In a strand-feeding device, the combination of a rotary element for feeding the strand, a friction-wheel connected to rotate said element, a reciprocable member having means for engaging the periphery of the wheel at opposite points thereon, means for reciprocating said member, and means actuated by said reciprocating member to cause the friction-wheel to be engaged alternately at opposite points on its periphery to turn the wheel in one direction to drive the strand-feeding means.

14. In a strand-feeding device for knitting and like machines, the combination of a rotary strand-feeding element, a friction-wheel connected to rotate said element, an eccentric mounting for said wheel, means for operating said mounting to shift the wheel into different positions, a reciprocating frame having opposed friction means for engaging the periphery of the wheel at opposite points thereon, means to reciprocate said frame, and means on said frame for engaging the eccentric-operating means to shift the wheel first in one direction and then in the opposite direction to cause it to alternately engage the friction means on the frame at opposite points on its periphery to rotate the wheel in a given direction.

15. In a strand-feeding device for knitting and like machines, the combination of strand-feeding means, a reciprocating carriage, means mounted independently of the carriage for operating the strand-feeding means, driving means on the carriage, and driven means on the operating means, said driving and driven means being arranged in longitudinally spaced relationship in the path of movement of the carriage whereby to permit relative movement of said driving and driven means 40 during a portion of the stroke of the carriage and driving engagement therebetween during the remainder of the stroke.

16. In a strand-feeding device for knitting and like machines, the combination of strand-feeding means, means for operating the strand-feeding means, a reciprocating carriage, driving means on the carriage, and driven means on the operating means, one of said driving and driven means having opposed parallel courses and the other means being positioned between the parallel courses and arranged in longitudinally spaced relationship in the path of movement of the carriage whereby to permit relative movement of the driving and driven means during a portion of 55 the stroke of the carriage and driving engagement therebetween during the remainder of the stroke.

ROBERT H. LAWSON.
